UNITED STATES PATENT OFFICE.

ROBERT P. BARNSTEAD, OF BOSTON, MASSACHUSETTS, ASSIGNOR, BY DIRECT AND MESNE ASSIGNMENTS, OF PART TO RUFUS H. SPALDING, OF SAME PLACE, AND JOHN C. BULLARD, OF CAMBRIDGE, MASSACHUSETTS.

APPARATUS FOR HEATING WATER.

SPECIFICATION forming part of Letters Patent No. 398,022, dated February 19, 1889.

Application filed February 18, 1888. Serial No. 264,636. (No model.)

To all whom it may concern:

Be it known that I, ROBERT P. BARNSTEAD, of the city of Boston, in the county of Suffolk and State of Massachusetts, have invented 5 certain new and useful Improvements in Apparatus for Heating Water, of which the following is a full, clear, and exact description. This improved apparatus for heating water in substance consists of a boiler of suitable construction closed on all sides, a pipe 10 suitably connected with a water-supply under pressure to enter and deliver water into the boiler at its lower portion, a pipe which leads from the upper portion of the water of 15 the boiler and makes when opened the hot-water discharge, and a pipe in communication with this discharge-pipe to conduct, when the discharge-pipe is closed, the water passing through it back into the water of the 20 boiler, and the whole so as to produce an automatic circulation of the water of the boiler through said discharge and return pipes, and all, as well known, in combination with a gas-burner or such like to heat the water of the 25 boiler under circulation, as stated, and connected to a suitable gas-supply, an expanding and contracting valve in the form of a 30 column of mercury, to which the gas-supply opens, to be closed on a rise and opened on a fall of the mercurial column, caused by the 35 rise and fall of the temperature of the water of the boiler, (it being located in the water, and preferably its lower portion,) and thus on the rise of the mercury to shut off and on a fall thereof to open the gas communication 40 with the gas-burner and an independent and always open communication of the gas with the gas-burner.

In addition to the above, under this invention 45 the mercurial column is provided with a stationary plunger capable of adjustment from the outside thereof, by which to regulate the normal height of the mercurial column, and, further, the inlet water-pipe is arranged to discharge directly against the mercurial column surrounded with a shell open to the water of the boiler to better and more closely confine the water so delivered at and about the mercurial column.

50 In the drawings forming part of this speci-

fication, Figure 1 is a side elevation of the water-heating apparatus. Fig. 2 is a central vertical section. Fig. 3 is a plan view. Fig. 4 is a horizontal section, line 4-4, Fig. 2.

In the drawings, A represents a boiler—a 55 vertical cylindrical shell closed on all sides.

B is a cylindrical casing, which rests on a suitable support and surrounds the boiler A, resting on a horizontal annular shelf, C, about the inside of the casing B. The upper end 60 of the casing is open.

D is a gas-burner of any suitable construction and having a stop-cock, (not shown,) as usual, for opening and closing it, and also located below the boiler in the lower portion of 65 the casing B, and all otherwise as well known, for its flame to act against the bottom of the boiler A and to heat the water entered and contained in the boiler.

E is the supply-pipe for the gas-burner D. 70 This pipe E passes from the gas-burner out through the opening F at the lower portion of the casing B, and thence upward horizontally across and above the top of the boiler, and it is connected with the gas-supply, as 75 hereinafter described.

H is a vertical pipe branching from the horizontal portion of the gas-pipe E, and leading through the top K of and into and nearly to the bottom of the boiler A, where it is 80 closed, making a chamber, L, to be charged with mercury, M, at a given level.

N is a vertical pipe within the branch pipe H of gas-pipe E terminating at its lower open end, O, just above the normal level of the 85 mercury in the chamber L of pipe H and dividing the passage of branch pipe into two separated vertical passages at their lower ends both open to the mercurial chamber L and at their upper ends each open at P to opposite end portions of the gas-pipe E. The gas from the supply-pipe E passes down one of the vertical chambers of the branch pipe H and at its lower end enters the mercurial chamber L, and thence up the other chamber 95 back to the gas-pipe E, to be conducted by it to the gas-burner D.

90 a is a perforation in the wall of pipe N, dividing branch pipe H into two vertical chambers, as above stated. This perforation is 100

cated above the mercurial chamber, and is for the passage of gas from one side to the other of pipe N, or, in other words, between the opposite end portions of the gas-pipe E 5 open to the vertical passages of branch pipe H, when the lower ends of said passages are closed by the rise of mercury in the mercurial chamber, as will hereinafter appear.

Q is a vertical plunger-rod entered into the 10 column of mercury and passing upward therefrom through the mercurial chamber and an opening, b, suitably packed, of the gas-pipe E, and projected at the outside of said pipe for convenience in adjusting it. Depressing this 15 plunger Q raises and lifting it lowers the height of the mercurial column, and thus the normal level of the mercury can be adjusted as to the plane of the lower open end of the gas-pipe N within the mercurial chamber L.

R is a vertical pipe entering the boiler A and terminating at its lower end, S, in close proximity to the walls of the mercury column M, toward which its said open and discharging end S is presented. This pipe R is for 25 supplying the boiler with water, and it is to be suitably connected with a water-supply under pressure.

T is a vertical shell open at top and bottom and surrounding the water-pipe R at its 30 discharging end to better and more closely confine the water discharged therefrom in contact with the walls of the mercurial chamber L.

U is a pipe opening to and leading upward 35 from the upper portion of the water of the boiler A. This pipe is the pipe for discharging hot water from the boiler, and its outer end opens to the water-passage of a faucet, U², through which, when opened, to discharge 40 the water, as may be desired, as also to a pipe, W, surrounding said pipe U and leading downward and opening to the water of the boiler at its lower portion. When the faucet is closed, the water of the boiler circulates through the 45 pipes U and W, passing upward through the pipe U, thence into the pipe W, and down into the water of the boiler. When the faucet is opened, the water of the boiler is discharged through it, it being delivered thereto from 50 the pipe U, to which, in the operation of the apparatus, it is delivered from its upper and hotter portion.

As the mercury column is submerged in the 55 water of the boiler, it is affected by the temperature thereof, rising in height as it increases and lowering in height as it decreases, and, as is plain, with a proper adjustment of the normal height of the mercurial column through the plunger Q relative to the open 60 end of the gas-pipe N the rise and fall of the mercury can be made to secure a closing and opening of the said end of the gas-pipe N at any desired temperature of the water in the boiler. By this means the supply of gas is 65 opened to or shut off from the gas-burner, thus enabling its flame to be regulated and to be increased and decreased as the tempera-

ture of the water in the boiler rises or falls, comparatively considered, but with the gas so shut off gas is still supplied to the gas-burner by passing to it from the gas-supply through the orifice a of the gas-pipe N, and which is above and not affected by the closing of the open end of said pipe on the rise of the mercury column.

75

In the apparatus described there is an automatic circulation of the water in the boiler through the pipes U and W, and also an automatic regulation of the gas-flame to prevent a heating of the water to a degree greater 80 than required or desired while still maintaining the gas-flame, and all in a manner enabling the apparatus to be readily adjusted to the requirements of its use and to be thoroughly automatic in operation.

85

Other kinds of burners—such as naphtha and gasoline—may be substituted for the gas-burner; but a gas-burner is most preferable.

Entering the water into the lower portion of the boiler, and taking the water from the boiler 90 at the upper portion thereof insures the delivery of hot water at the faucet when it is opened. Entering the water directly about the mercurial chamber and against the mercurial column thereof secures its direct action at its lowest 95 temperature on the mercury, and so the quickest and most effective heating of the whole contents of the boiler to the desired degree is insured, for the reason that the supply of gas to the burner is maintained practically to its 100 fullest extent until the water immediately about the mercury column has reached the temperature desired, this water being the last, comparatively considered, to attain such temperature.

105

The shell T, by confining cold water as it is entered directly about the walls of the mercurial chamber L, insures the immediate fall of the mercurial column, opening the vertical passages of the branch pipe H of gas-pipe E 110 to the passage of gas to the burner to increase its flame, to the end that the water of the boiler cooled by the entrance of water, as stated, shall be the more quickly again brought to the temperature desired.

115

Having thus described my invention, what I claim, and desire to secure by Letters Patent, is—

1. The combination of boiler A, gas-burner D, to heat boiler, pipe E, to supply gas to burner, and pipe H, branching from pipe E and leading into water of boiler, and at its lower portion adapted to contain mercury and along its height divided into two separate gas-passages at their lower ends both open to mercurial chamber L and at their upper ends open to opposite end portions of gas-pipe E, and between their ends having a supplemental communicating gas-passage, a, located above mercurial chamber, substantially as described, 125 for the purpose specified.

130

2. The combination of boiler A, gas-burner to heat boiler, pipe E, to supply gas to burner, pipe H, branching from pipe E and leading

into water of boiler, and at its lower portion adapted to contain mercury and along its height divided into two separate gas-passages at their lower ends both open to mercurial chamber L and at their upper ends open to opposite end portions of gas-pipe E, and between their ends having a supplemental communicating gas-passage, a, located above mercurial chamber, and a plunger, Q, stationary 5 in mercurial chamber and extended to outside of chamber, to be raised and lowered from the outside thereof, substantially as described, for the purposes specified.

3. The combination of boiler A, gas-burner 15 to heat boiler, pipe E, to supply gas to burner, pipe H, branching from pipe E and leading into the water of boiler, and at its lower portion adapted to contain mercury and along its height divided into two separate gas-passages, and at their lower ends both open to 20 mercury of pipe H and at their upper ends open to the opposite end portions of gas-pipe E, and between their ends having a supplemental communicating gas-passage, a, located 25 above the mercurial chamber, and a water-supply pipe, R, entering boiler and arranged to discharge against walls of mercurial chamber.

ber of pipe II, substantially as described, for the purposes specified.

4. The combination of boiler A, gas-burner 30 to heat boiler, pipe E, to supply gas to burner, pipe H, branching from pipe E and leading into the water of boiler, and at its lower portion adapted to contain mercury and along its height divided into two separate gas-passages, and at their lower ends both open to 35 mercurial chamber L and at their upper ends open to opposite end portions of gas-pipe E, and between their ends having a supplemental communicating gas-passage, a, located above 40 the mercurial chamber, a water-supply pipe, R, entering boiler and arranged to discharge against walls of mercurial chamber of pipe H, and a shell, T, surrounding water-supply pipe at its discharge N and open to the water 45 of the boiler, substantially as described, for the purposes specified.

In testimony whereof I have hereunto set my hand in the presence of two subscribing witnesses.

ROBT. P. BARNSTEAD.
